UNITED STATES PATENT OFFICE

McCLELLAND BARCLAY, OF NEW YORK, N. Y.

DESIGN FOR AN ELECTROLIER FOR TELEPHONE INSTRUMENT

Application filed September 26, 1931. Serial No. 41,237. Term of patent 14 years.

To all whom it may concern:

Be it known that I, McCLELLAND BARCLAY, a citizen of the United States, residing at No. 730 Fifth Avenue, New York city, in the county of New York and State of New York, have invented a new, original, and ornamental Design for an Electrolier for Telephone Instrument, of which the following is a specification, reference being had to the accompanying drawings, forming part thereof.

Figure 1 is a perspective view showing my electrolier for telephone instrument and Figure 2 is a side view showing my electrolier for telephone instrument.

I claim:

The ornamental design for an electrolier for telephone instrument as shown.

McCLELLAND BARCLAY.
